UNITED STATES PATENT OFFICE.

JOHN N. SWANSON, OF HOUSTON, TEXAS.

CHARGE-FIRING PIN.

1,290,680.

Specification of Letters Patent.

Patented Jan. 7, 1919.

Application filed January 14, 1918. Serial No. 211,846.

To all whom it may concern:

Be it known that I, JOHN N. SWANSON, a citizen of the United States, residing at Houston, in the county of Harris and State 5 of Texas, have invented certain new and useful Improvements in Charge-Firing Pins; and I do declare the following to be a full, clear, and exact description of the invention, such as will enable others skilled 10 in the art to which it appertains to make and use the same.

My invention relates to improvements in firing pins for charge laden bodies such as projectiles, aerial bombs and torpedoes; and 15 the principal object is to provide a comparatively simple yet highly efficient arrangement of parts which may not easily be fired accidentally, yet will be very sensitive when the travel of the carrying body is 20 checked.

With the foregoing general object in view, the invention resides in the novel features of construction and unique combinations of parts to be hereinafter fully 25 described and claimed, the descriptive matter being supplemented by the accompanying drawings which form a part of this specification and in which:

Figure 1 is a side elevation of the invention applied;

Fig. 2 is a longitudinal section showing the normal positions of parts;

Fig. 3 is a similar view illustrating the relation of parts when the travel of the projectile or the like is checked;

Fig. 4 is a view similar to Figs. 2 and 3 but illustrating the manner in which the firing pin is forced against the percussion cap;

Fig. 5 is a vertical transverse section on the plane of the line 5-5 of Fig. 3; and

Figs. 6 and 7 are transverse sections of Fig. 2 on the planes indicated by the lines 6-6 and 7-7 respectively.

In the drawings above briefly described, the numeral 1 designates a preferably cylindrical casing which is shown in the present embodiment of the invention as positioned 45 within the charge carrying head 2 of a projectile 3, the rear end of said casing being threaded externally for mounting the same as shown at 4. The front end of the cylinder 1 is closed by a plate 5 having a central socket 6 on its inner side, said socket receiving the front end of a longitudinally disposed firing pin 7 which is positioned co-

axially in the casing, the rear end of said pin being provided with a prong or the like 8 which is spaced forwardly from a percussion cap 9 or other suitable charge firing device which is used to ignite the priming charge 10, this charge being shown as carried in a suitable casing 11 held by a plug 12 within a ring 13 which is threaded into the rear end of the casing 1. When the charge 11 is ignited, the flame therefrom passes from the casing through one or more openings 14 therein to fire the charge 15 in the head 2. The opening 14 is preferably plugged with some soft or fusible material 70 which will prevent powder entering the casing 1, yet will readily give way or burn when the charge 10 is fired.

An operating weight 16 is provided for the firing pin 7, said weight being slidable 75 forwardly in respect to said pin as will be clear by comparing Figs. 2 and 3, and it is intended that when the projectile strikes a body, the momentum of the weight 16 shall move the same forwardly along the pin to 80 the position depicted in Fig. 3, thus compressing a coiled spring 17 which is interposed between said weight and the end plate 5 of the casing 1. This spring then immediately exerts its tension to return the weight 85 16 rearwardly, but in the meantime this weight has been operatively connected to the firing pin by a clutch mechanism.

This mechanism includes a pair of dogs 18 preferably formed by bending the ends 90 of a spring 19 as shown in Fig. 6, said spring being suitably mounted on one end of the weight 16. The dogs 18 normally seat within a shallow groove or recess 20 formed around the pin 7 as shown in Fig. 2, but 95 these dogs are moved bodily forward with the weight 16 and are adapted to snap into a second and deeper annular groove or recess 21 which is also formed in pin 7. The dogs then abut the shoulder 21' at one end 100 of the recess 21 as shown in Fig. 3, so that the return movement of weight 16 will correspondingly move the firing pin to bring its prong 8 into contact with the cap 9.

For normally holding the pin 7 against 105 movement and for accelerating the speed of this pin when the tension of spring 17 comes into play, a double-acting spring 22 is provided, said spring being of circular form substantially concavo-convex in transverse 110 section, the edge of said spring being anchored between the ring 13 and the adjacent

portion of the casing 1 whereas the center of said spring is secured to the pin 7. The convex face of spring 22 normally faces forwardly, but when the spring 17 forces the weight 16 and the pin 7 rearwardly, the tension of spring 22 is overcome so that it suddenly bows in the opposite direction. Since the movement of spring 22 is extremely sudden after the bowed portion thereof has been forced into the plane of the edge of the ring, it will be obvious that the speed of the pin 7 will be so accelerated as to increase the power of said pin to insure proper firing of the cap 9.

15 In use, the device is suitably installed upon a projectile, an aerial torpedo or a submarine torpedo, so that the firing pin 7 extends longitudinally of the direction of travel and the percussion 9 is located in rear of said pin. With the parts so arranged, spring 22 normally holds the firing pin 7 against possible contact with the cap 9 and since the dogs 18 then engage the shallow recess 20 considerable movement of the weight 16 against the tension of spring 17 will be permitted without moving pin 7, it being necessary that the carrying body be suddenly brought to a stand still in order that the weight shall move forwardly with sufficient force to compress the spring 17 to the position of Fig. 3 and simultaneously engage dogs 18 with the recess 21. It is thus insured that ordinary handling will not endanger the lives of those in the vicinity.

From the foregoing, taken in connection with the accompanying drawings, it will be obvious that although my invention is of extremely simple nature, it will be highly efficient and sensitive when its use is required, yet proof against premature firing by rough handling. Since probably the best results are obtained from the several specific details shown and described, these details are preferably employed, but I wish it understood that within the scope of the invention as claimed, numerous minor changes may well be made. For instance, although weight 16 is shown as provided with a filler 16' of heavy material, such filler might well be eliminated in some cases.

I claim:

1. In combination, a firing pin adapted to be disposed longitudinally of a charge laden body, a charge firing cap spaced from the rear end of said pin, an operating weight for said pin slidably relatively thereto when the travel of the carrying body is checked, a spring tensioned by such forward sliding of said weight for returning the latter rearwardly, and a clutch for connecting said weight and said pin upon the rearward return of the former, whereby said pin will be moved rearwardly to fire said cap.

65 2. A structure as specified in claim 1, said

clutch consisting of a dog on said weight and a shoulder on said pin with which said dog engages when said weight has moved forwardly.

3. A structure as specified in claim 1, said clutch consisting of a spring arm on said weight, and a shoulder on said pin with which said spring arm engages when said weight has moved forwardly, said pin having a shallow recess in which said spring arm normally rests.

4. In combination, a charge firing cap, a pin for firing said cap, means for moving said pin toward said cap, and a double-acting spring for normally holding said pin against movement and for accelerating the speed of said pin when said pin moving means comes into play.

5. A structure as specified in claim 4, said spring being of circular form substantially concavo-convex in section, the center of said spring engaging said pin and the edge of said spring being anchored.

6. In combination, a firing pin adapted to be disposed longitudinally of a charge laden body, a charge firing cap spaced from the rear end of said pin, an operating weight for said pin adapted to move forwardly by momentum when said charge laden body is checked in its forward travel, a spring tensioned by said forward movement of said weight for returning the latter rearwardly to force said pin against said cap, and a double-acting spring for normally holding the pin against movement and for accelerating the speed of said pin as it moves rearwardly.

7. In combination, a firing pin adapted to be disposed longitudinally of a charge laden body, a charge firing cap spaced from the rear end of said pin, an operating weight for said pin adapted to move forwardly by momentum when said charge laden body is checked in its forward travel, a spring tensioned by said forward movement of said weight for returning the latter rearwardly to force said pin against said cap, and a double-acting spring for normally holding the pin against movement and for accelerating the speed of said pin as it moves rearwardly, said spring being of circular form substantially concavo convex in cross section, the center of said spring engaging said pin and the edge thereof being anchored.

8. In combination, a cylindrical casing adapted to be disposed longitudinally of a charge laden body, a priming charge at the rear end of said casing including a percussion cap, a closure for the front end of said casing having an internal central socket, a longitudinal firing pin positioned centrally in said casing with its front end received slidably in said socket and its rear end spaced in advance of said percussion cap, a weight slidable in said casing for operating

said pin, said weight surrounding said pin, means for normally holding said pin forwardly, a spring normally forcing said weight rearwardly, said weight being adapted to slide forwardly and compress said spring when the speed of the carrying body is checked, and means for connecting said weight with said pin when the former has moved forwardly, whereby the return rearward movement of said weight under the

tension of said spring will force said firing pin rearwardly against said percussion cap.

In testimony whereof I have hereunto set my hand in the presence of two subscribing witnesses.

JOHN N. SWANSON.
